STOP WATCH TESTING APPARATUS

William Ogle Bennett, Jr., Lancaster, Pa., assignor
to Hamilton Watch Company, Lancaster, Pa.

Application May 3, 1943, Serial No. 485,518

9 Claims. (Cl. 73—6)

This invention is directed to an apparatus for testing stop watches over a definite period of time.

Heretofore in the testing of stop watches the starting and stopping of the watch is done by synchronizing with an audible signal occurring, say, once each second, and is therefore entirely dependent on the skill and coordinating reflexes of the operator.

It is the object of this invention to remove any element of skill and make the testing a fool proof ordinary mechanical operation.

It is the purpose of this invention to provide an apparatus which will accurately and for any predetermined period of time compare the running of a timing mechanism with a standard.

It is a further purpose to provide an apparatus by means of which watches can be timed for a given period of time in groups and at intervals much smaller than the period being measured by said watches.

It is a still further object to provide a covered traveling belt which conveys the watches from the starting point to the stopping point.

It is a still further object to provide means for preventing removal of the watches when once placed on the belt until the time for placing the watch in stopping position.

It is a still further object to provide a measuring dial which gives each watch a number and position so that if the time is for a long period the watches may be removed from the machine for an hour or more and returned and each exactly timed for the desired period.

It is a further object to provide means for completely stopping the machine should there be even a momentary failure of the power line current.

It is a still further object to provide a pair of synchronized solenoids serving to start and stop the watches.

The invention is illustrated in the accompanying drawings in which:

Fig. 1 is a front elevation.

Fig. 2 is a top plan with the rear cover removed and the ends of the vertical partition shown in section.

Fig. 3 is a wiring diagram showing the electrical parts diagrammatically, which parts are omitted from the other views.

Fig. 4 is a detail view of the contact making device.

The apparatus as illustrated has a base 1 with a central vertical partition 2 dividing the base into a front base 4 and back base 3. A vertical

5 front panel 5 extends along the forward edge of the front base leaving two free end areas 6 and 7. Axes 8 and 9 are carried by said front panel and the vertical partition and in turn carry pulleys 10 and 11 over which an endless belt 12 travels. A platform 13 supports the belt and an adjustable roller 14 is arranged to keep the belt taut. Shields 15 extending over the pulleys 10 and 11 serve as guards and help to position the watch at one end by narrowing the available space on the belt and prevent the watch being carried over the pulley at the other end, the edge 16 of the shield serving as a stop for the watch.

10 The invention is illustrated by an apparatus 15 designed to give stop watches a thirty second test but by changing the gear ratio or the speed of the motor and the length of the traveling belt, all mechanical adjustments the test could be for any predetermined period. Ordinarily stop watches are put through a short test of approximately thirty seconds several times which gives an average reading and also tests the operating button, and a long test which is generally one hour.

15 The mechanism for driving the belt is a motor 17 which is of the synchronous type turning 60 R. P. M. and is driven from a source of standard frequency current which must be accurate. The motor drives a geared wheel 18 through a pinion 19, the wheel 18 being keyed to the shaft 8 and the ratio being such that the shaft 8 makes ten revolutions per minute. The pulleys 10 and 11 are of such a size that the belt makes 6 inches travel every six seconds and the shafts 8 and 9 20 are so spaced that the travel of the belt from one to the other is accomplished in thirty seconds. The belt is covered by a hinged cover board 21 extending over its central portion and preventing the removal of the watch before twenty-four seconds have passed. In this way removal of the watch from the belt is prevented until after the twenty-fourth second after the watch is started. This period could, of course, be changed to any convenient timing period but 25 for purposes of illustrating the invention specifically the timing period will be considered thirty seconds, which is one of the tests usually given stop watches.

30 The mechanism for starting and stopping the watches is shown at 22 and 23, the mechanism being identical and operated every six seconds. Solenoids 24 having movable cores 25 are connected to operate simultaneously. Springs 26 are carried on pivotally mounted blocks 27 and are 35 adjustably connected at one end to the cores 25.

through spring tensioned screws 28 and at the other end support striker blocks 29 formed of cork or other suitable material. The ends of the striker blocks project partly through openings 30 and 31 in the vertical partition 2 where they engage the starting button 32 on the watches 33 as they are presented. The adjustable spring tensioning means 28 allow the striker block to be adjusted for either a light or heavy blow.

The dial 20 is designed with two hands 34 and 35, one of which rotates once every minute and designates the single watches struck by the striker while the other hand 35 rotates once every hour and designates the watches in groups of ten or more, making it possible when running through a batch of five hundred watches to know just which watch is being tested. This is important when a test of longer duration than thirty seconds is run. If, for example, it is desirable to allow the watches to run exactly one hour.

The electrical system for operating the apparatus is diagrammatically illustrated in Fig. 3 and includes two power lines, a source of ordinary current 36 and a source of standard frequency current 37 which latter source must be accurate as the timing depends on the running of the motor at an exact speed. A switch 38 initially completes the circuit for both lines and current flows along standard frequency wires 39 and 40. Wire 40 connects direct to the motor while wire 39 is interrupted by a push button switch 41 which when closed energizes the motor 17 as well as the solenoid 42. The closing of solenoid 42 carries the current to the motor through the solenoid by-passing the push button switch 41. This arrangement makes even a momentary break in the current supply stop the motor necessitating operation of the push button to again start operation. A signal light 43 is connected to warn the operator that the motor has stopped but that switch 38 is closed. This arrangement prevents the failure of current for even one second to be put down as error in the watch. The solenoids 24 are energized through contacts 44 and 45 which are brought together with every revolution of the wheel 18 by a pin 46 carried on said wheel striking the cam surface 47 of contact 44. Closing of switch 38 on the source of supply sends the current through wires 48 and 49, wire 48 connecting directly with solenoids 24 and solenoid 50. Momentary closing of contacts 44 and 45 operates solenoid 50 which completes the circuit to solenoids 24. These operate simultaneously to swing the striker blocks into watch starting or stopping operation. Contacts 44 and 45 are mounted in insulation block 51 carried on the back base 3. The electrical apparatus such as wires, switches, solenoids are not shown except diagrammatically in Fig. 3 where their function is the closing of a circuit.

The operation of the thirty second test is carried out as follows. The trays of watches about to be tested are arranged conveniently to an operator seated before base portion 6. One of the trays is placed adjacent to portion 6 and the apparatus started by closing switch 38 and operating push button 41. In the next six seconds the operator having first wound all watches to be tested holds the stem of a watch at opening 30 where when the indicator hand reaches 1 the striker block hits the plunger 32 of the watch, thus starting the sweep second hand 51. The watch is placed on the traveling belt and a second watch is held to the opening 30 to await the action of the striker block as the indicator hand 34 passes

2. This is repeated until the test is concluded, starting the watches at six second intervals. Twenty-four seconds after the first watch is started it reaches the end of the cover board 21 and may be taken up by a second operator seated in front of base portion 7 with an empty tray to receive the watches. The second operator presents the watch to the opening 31 after the twenty-fourth second and before the thirtieth, the striker block 29 contacting the plunger 32 stops the watch exactly thirty seconds after starting. Each of the watches are stopped at six second intervals and placed in the trays. After the test is over the watches are examined and the error noted. The length of the test is, of course, variable and the apparatus could be adapted for tests of any duration.

What is claimed is:

1. An apparatus for timing stop watches comprising an accurate source of time, a pair of spaced striker blocks actuated at predetermined intervals controlled by said source of time to respectively start and stop a stop watch and a continuously operating conveying means for said stop watches said conveyor means extending between said spaced striker blocks and timed to receive a started stop watch from the operator at one striker block and present said watch after an exact time interval convenient to said other striker block.

2. An apparatus for timing stop watches comprising a pair of spaced striker blocks, means for actuating said striker blocks simultaneously at predetermined intervals to actuate the starting and stopping mechanism of a stop watch, a continuously operating conveyor extending between said striker blocks and means for operating said conveyor so that its rate of travel is in exact relation to the time period between actuation of the striker blocks, said conveyor receiving a started stop watch adjacent one of said striker blocks and presenting said watch convenient to said second striker block after a predetermined time interval.

3. An apparatus for timing stop watches comprising an accurate source of time, a pair of spaced striker blocks actuated simultaneously at predetermined intervals to start and stop a stop watch, a continuously operating conveying means for said stop watches extending between said spaced striker blocks to convey the started watch from one of said striker blocks to a position adjacent said other striker block after a predetermined time interval.

4. An apparatus for timing stop watches comprising an accurate source of time, a pair of spaced striker blocks, means for actuating said striker blocks simultaneously and at exact predetermined equal intervals, timing means for controlling the actuation of said striker blocks, a conveyor belt moving between said striker blocks, timing means serving to move the conveyor belt whereby a watch on the conveyor belt passes from a position adjacent to one of said striker blocks to a position adjacent to the other of said striker blocks in an even multiple of the time interval between the periods of actuation of said striker blocks, and means preventing access to the conveyor belt except adjacent the striker blocks.

5. An apparatus for timing stop watches comprising a base, a vertical panel mounted on said base, a pair of spaced striker blocks operating through holes in said panel, means for actuating said striker blocks at predetermined intervals, a conveyor belt mounted on said base and extend-

ing from one striker block to the other, a cover for said conveyor belt extending from a small exposed portion adjacent one striker block whereby stop watches set in operation by the first striker block and deposited on the conveyor belt are not for presentation for positioning at said second striker block until after a predetermined time interval, said time interval being slightly less than an exact multiple of the time interval between the actuation of said striker blocks.

6. An apparatus for testing timepieces, including stopping and starting means for a timepiece, means for operating said starting and stopping means at predetermined period intervals, and means for conveying a timepiece following operation of the starting means to a position adjacent the stopping means for effective operation of the stopping means on the timepiece, the conveying means having a period of operation less than an exact multiple of the period of operations of the starting and stopping means predetermined as the measure of the timepiece test, whereby a timepiece manually subjected to the operation of the starting means may be transferred to and delivered by the conveying means for manual co-

operation with the stopping means for that particularly predetermined operation of the stopping means.

7. A construction as defined in claim 6 wherein the conveying means maintains the timepiece beyond the influence of the operator during the conveying period.

8. An apparatus for testing timepieces, including a starting element for starting the timepiece, a stopping element for stopping the timepiece, means for operating said elements in synchronism at the same predetermined and equal time intervals, and a conveyor to receive a timepiece after operation of the starting element thereon and to convey such running timepiece to a position adjacent the stopping element, the conveyor having a period of operation between reception and delivery points of the timepiece slightly less than the time period required for a predetermined number of operations of the starting and stopping elements.

9. An apparatus as defined in claim 8 including an indicator for registering the number of operations of the striker block.
